UNITED STATES PATENT OFFICE.

GEORGE E. DAVIS, OF DUBUQUE, IOWA.

POWER-HAMMER.

No. 888,391.

Specification of Letters Patent.

Patented May 19, 1908.

Application filed August 8, 1906. Serial No. 329,734.

To all whom it may concern:

Be it known that I, GEORGE E. DAVIS, a citizen of United States, residing at Dubuque, in the county of Dubuque and State of Iowa, have invented certain new and useful Improvements in Power-Hammers, of which the following is a specification.

My invention relates to improvements in power hammers, and refers particularly to 10 the type known as helve hammer and used in blacksmithy and similar work.

The main object of my invention, is the provision of a hammer of this type which will be well balanced so as to admit of rapid reciprocating motion, and a further object is to provide cushioning means to take up the jar of the blow and relieve the machine of the great strain caused thereby.

My invention also has for its object, to provide 20 a helve hammer which may be controlled at will by means of a single lever, and which will be very light, simple and durable in construction.

With these objects in view, my invention 25 consists of an anvil carrying a die, standards supporting a helve carrying a die to coact with the die of the anvil, a shaft and a driven pulley thereon connected by flexible means and adapted to operate the helve, a loose belt 30 on the driven pulley, an idler pulley adapted to engage said belt, means for operating the idler, and a brake to the driven pulley automatically set when the idler is disengaged from the belt.

35 My invention further consists of a power hammer embodying certain other novel features of construction, combination and arrangement of parts substantially as disclosed herein.

40 Figure 1, is a top plan view of my improved power hammer. Fig. 2, is a side elevation thereof. Fig. 3, is a detail view partly in section to show the braking means and belt tightener, the full lines indicating the normal 45 inoperative position, and the dotted lines indicating the operative position of the parts. Fig. 4, is an end elevation of the upper, middle and lower clamping blocks and staple bolt for clamping the helve to the helve shaft. 50 Fig. 5, is a side elevation of the lower clamping block. Fig. 6, is a top plan view of the middle clamping block. Fig. 7, is a similar view of the upper clamping block. Fig. 8, is an end elevation thereof. Fig. 9, is a side 55 elevation of the journal bearings for the helve shaft and the web connecting the same.

Fig. 10, is a side elevation of the hammer helve with the hammer in position therein. Fig. 11, is a detail perspective view of the hammer. Fig. 12, is a top plan view of the 60 hammer helve showing the means for securing the swage block therein. Fig. 13, is a detail perspective view of the swage block.

In the drawings: the numeral 1, designates the anvil of the machine preferably of 65 tapering construction to provide a broad supporting base, and having the die block 2, suitably secured in the head thereof. A shaft 3, is journaled in and passes through a portion of the base of the anvil, and secured 70 at its ends to said shaft, is a U-shaped foot lever 4, which practically surrounds the base of the anvil. Secured at one end of the shaft is a rocker arm 5, and pivoted to said arm is a shift rod 6, whose purpose will be described 75 later.

Stationed at the proper distance from the anvil, is a hollow base or platform 7, upon which is mounted the pair of columns or standards 8, provided with suitable brace 80 rods 9. Cap pieces 10, connected by a web 10', (see Fig. 9) are secured upon the standards and are semi-circular at their upper ends to support the lower half 11, of the journal box, and bolted to said caps are the upper 85 halves or shells 12, which form the complete journal bearings for the helve shaft 13. The helve or lever of the hammer consists of two substantially parallel rods or bars 14, connected by the spacing bolts 15. A clamp 90 block 16, is mounted upon the upper side of the helve shaft and is provided with grooves or channels 17, to receive the bars of the helve. A cap 18, having complementary grooves is fitted upon the hammer lever, and a staple bolt 19, passes round the clamping block 19', on the lower side of the shaft, through the clamp block and cap, and is provided on its ends with nuts 20, to properly 95 secure the helve in position upon the shaft. 100 In the forward end of the helve or hammer lever is secured the hammer block or die 21, and the block is secured in position by means of the bolts 22, which engage openings provided for that purpose in the ends of the 105 block, so that by the removal of one bolt and the loosening of one other, the die may be entirely removed and reversed or changed as necessary. In the rear end of the helve is secured a block 23 and secured to said block by 110 means of the bolts 24 and retaining plate 25, is a leaf spring 26, composed of a series of

spring bands or leaves as shown. The outer ends of the leaf spring are connected by the links 27, to the forked end 28, of the pitman 29.

Mounted in bearings 30, on the base parallel to the helve shaft, is a shaft 31, having rigidly mounted thereon the flanged pulley 32. On the outer end of the shaft 31, is keyed a slotted crank disk 33, and a pitman sleeve 34, is secured to the disk by means of 10 a bolt 35, whose head engages the slot in the disk, passing through the wrist pin upon which the pitman sleeve rotates. This pitman sleeve or socket is adapted to receive the pitman, which is adjustably secured 15 therein by means of the set screw or bolt 36. Mounted in journal bearings 37, adjacent the shaft 31, is a rock shaft 38, provided with a forked extension 39, formed with a sleeve or collar 40. Engaged in said sleeve and adjustably secured therein by means of the set screw 41, is a rod 42, formed with forked arms 43, in which is rotatably mounted the 20 idler pulley 44, adapted to engage the loose belt 45, passing over the driven pulley 32.

25 Extending downward from the rock shaft 38, is a rocker arm 46, carrying a brake block 47, preferably of wood and adapted to engage the driven pulley. To the lower extended end of the rocker arm, is connected a link 48, 30 to which is secured a spiral spring 49, and to the other end of the spring is connected a rod 50, which passes through and is adjustably secured in the base by means of the adjusting nut 51. This spring exerts its tension to 35 cause the brake block to engage the driven pulley. An arm or lever 52, is mounted upon the extended end of the rock shaft and is pivotally connected with the shift rod 6, so that by depressing the foot lever of the anvil, 40 the brake is thrown out of engagement with the pulley, the idler tightens the belt on the said pulley, and the machine is set in operation.

It will be seen that the machine is capable 45 of various adjustments. The length of the stroke may be changed by means of the slotted crank disk connection, the tension of the leaf spring may be altered by adjusting the length of the pitman links, the idler pulley may be moved to suit the tightness of the belt on the driven pulley, and the tension of the brake spring may be adjusted at will. The speed of the machine may be varied by 50 changing the pressure on the foot lever to tighten or release the belt, and the machine may be instantly stopped by removing pressure on the foot lever, when the spring automatically sets the brake.

From the foregoing description taken in

connection with the drawings it will be obvious that I have provided a power hammer which is capable of handling a great variety of work, and which is thoroughly practical and desirable in every particular.

As shown in the detail view, (Fig. 11), the hammer is formed with a flat face and a tapering or pointed wedge-shaped face so that it is adapted for different character of work. On one end of the hammer is provided a groove 53, and on the opposite end, 60 a series of parallel grooves 54. The grooves are adapted for engagement with the bolts in the end of the hammer lever, and the series of grooves or channels allows the block to be tilted or set at an angle in the end of the 65 lever so as to strike the work parallel to the face of the anvil. When it is desired to use a swage in place of the hammer, the pair of blocks 55, are secured in the end of the helve in the same manner as the hammer, and the 70 meeting edges of the blocks are formed with complementary cut or recessed portions to provide a rectangular opening 56. The swage block 57, is of the desired size and shape and is provided with a central stud or 75 projection 58, adapted to be engaged in the opening between the clamping blocks 55, so that when the bolts are tightened, the swage is securely clamped in the end of the helve.

The pitman may be lengthened or shortened at will to adapt the machine to work of various sizes so that the hammer will strike the proper blow with reference to the size of the work.

I claim:

1. A helve for power hammers comprising in the combination with a supporting shaft, of a pair of spaced parallel bars, spacing bolts for securing the parallel bars together, the spacing bolts adapted to clamp a hammer or 95 swage blocks between the parallel bars, and clamping means for securing the helve upon the supporting shaft.

2. In a power hammer, the combination with journal bearings and a supporting shaft 100 mounted therein, a helve composed of a pair of spaced parallel bars connected by spacing and clamping bolts adjustably clamped upon the shaft, a hammer provided with a series of grooves to receive the clamping bolts so as to 105 be adjustably clamped between the parallel bars of the helve.

In testimony whereof I affix my signature in presence of two witnesses.

GEORGE E. DAVIS.
